CUTTER

William P. Dooley, St. Albans, W. Va., assignor
to American Viscose Corporation, Wilmington,
Del., a corporation of Delaware

Application August 25, 1947, Serial No. 770,405

1 Claim. (Cl. 164—38)

1

This invention relates to a cutting device and is particularly concerned with maintaining a cutter member in efficient cutting engagement with a shear member co-operating therewith to effect cutting of material fed thereto.

In the past, it has been customary to urge one of such members (either the cutter or the shear member) against the other by resilient means which was backed up by a fixed bearing element. Since it is characteristic of resilient means, such as a helical spring, that the stress is proportional to the strain, it is clear that when such resilient means is backed up by a fixed element and undergoes a large strain or deformation, either compression or extension, the force urging the members together may become excessively high and subject the parts to extreme wear.

In accordance with the present invention, one of the cutter or shearing members is urged against the other by resilient means and such resilient means is backed up by floating means, which may for example be gravitationally urged against the resilient means. In this manner, the force applied through the resilient means is more evenly controlled and is relatively constant except for momentary fluctuations which may occur occasionally but even when such fluctuations occur, they do not cause such excessive stresses as heretofore since they are controlled by the inertia of the moving parts and particularly of the floating means which backs up the resilient means. Other objects and advantages of the invention will be apparent from the drawing and the description thereof hereinafter.

In the drawing, illustrative of the invention, Figure 1 is a plan view of one embodiment of the invention, and

Figure 2 is an elevation thereof.

In Figures 1 and 2, the shear member is illustratively shown as a disc 3 mounted in a bearing 4 for rotation by means of a shaft 5 and a pulley 6. This shear member is provided at the top with a generally concentric entrance 7 for the material to be cut, which may take the form of endless filaments, or large or small bundles thereof, yarns, strands, cords, or even relatively thick strips of material of indefinite length. The entrance 7 communicates with a radial passage 8 terminating in an opening 9 in the periphery of the disc 3.

The cutter member comprises a knife 10 secured within a holder 11 formed in the end of a projecting arm 12 extending from a bearing sleeve 13 which is secured to a post 14 by means of a set screw 15. The post 14 is mounted within a bearing sleeve 16 in a bracket 17, which

bracket also has an arm 18 extending outwardly to support a bracket 19 which may be secured thereby by means of cap screws 20. To the other end of the post there is secured an arm or bracket 21 by means of a set screw 22. The outer end of the bracket 21 is provided with a socket or housing 23 which in turn is provided with a cap 24 threadedly secured thereon. Within the socket 23 a hollow sleeved member 25 is provided, about 10 the sleeve of which a coil spring 26 is disposed. An element 27 is slidable within the recess of the socket and may be provided with two projecting splines 28 which fit within ways 29. The element 27 bears against one end of the spring 26 and is adjustably secured to a rod 30 which extends freely through an opening 31 in the cap 24 and within the hollow portion of the sleeved fitting 25. The bearing element 27 may be moved from different adjusted positions by loosening 15 the set screw 32, rotating the rod 30 which has threaded engagement with the element 27 and retightening the set screw 32 when the desired adjustment is attained.

The bracket 19 may be made in the form of a 25 yoke as shown clearly in Figure 1 so that a lever 33 can be pivotally supported by the pin 34 extending into the two arms of the yoke 19 on each side of the lever 33. The rod 30 terminates in a rounded bearing portion 35 against which one face 36 of the lever 33 may bear. The lever 33 30 has a threaded portion 37 upon which a weight 38 may be secured as by means of the lock nuts 39 and 40.

In operation, the material to be cut is fed into the entrance 7 and passes out through the opening 9, while the disc 3 is rotated by means of the pulley 6. Such rotation may be at various speeds including such as will develop sufficient centrifugal force within the material proceeding through the passage 8 as to thereby constitute 40 the sole feeding force of the material through the device. On the other hand, rotation may be at somewhat lower speeds and in that case, the feeding of the material through the disc may be assisted by directing a blast of fluid, such as 45 air or water, into the entrance 7 along with the material, as is conventional. Periodically, the material projecting outwardly from the disc is cut by the knife 10 as the opening 9 passes such knife. When the material strikes the knife 10 50 it exerts a force tending to swing the knife away from the disc and the shock of this force is partially absorbed by the spring 26 and partially transmitted to the floating lever 33. However, it will be noted that the force is always maintained within controlled limits as determined by

the inertia characteristics of the mounting and particularly of the floating system of which the weight 38 is the most important part. While the spring 26 may undergo a momentary compression while the impact is transmitted to the floating system, it is quickly restored to dynamic equilibrium in which the force exerted upon the knife and urging it against the shear member 3 is substantially the normal value. This results because of the movement allowed by the bearing member 27 backing up the spring so that the spring does not undergo as great a strain or deformation as it would have had to do were the member 27 held in fixed position. It will also be noted that when the diameter of the disc 3 is reduced because of wear, it is unnecessary to re-adjust the knife mounting since the same force is exerted upon the knife regardless of its angular disposition about the post 14. Even if, as a result of such wearing of the periphery, it is necessary to adjust the setting of the knife 10 within the holder 11 in order to maintain a desired angular relationship between the knife 10 and the disc 3 such adjustment can be made without necessitating a re-adjustment of the resilient means. Thus it is seen that the present invention avoids human error that could occur in re-adjusting the resilient tensioning means.

It is to be understood that changes and variations may be made without departing from the spirit and scope of the invention as defined in the appended claim.

I claim:

A cutting device for cutting continuous fil-

amentary material to discontinuous lengths comprising a disc-shaped shear member having a channel extending therethrough to guide a strip of the material to be cut radially outwardly therefrom, means for rotating the shear member about its axis, a fixed bracket, a shaft rotatable in the bracket about an axis generally parallel to that of the shear member, a knife fixedly mounted on the shaft for pivotal motion about the axis of the shaft to dispose its cutting edge adjacent the periphery of the member, means for urging the knife edge into cutting relationship against the periphery of the member comprising an arm fixedly secured to the shaft, an element movably mounted on the arm, resilient means interconnecting the element and arm for resiliently transmitting force from the element to the arm, and a weighted lever for urging the element against the resilient means, said lever being pivotally mounted on an axis transverse of the axis of the shaft:
